UNITED STATES PATENT OFFICE.

FRANK A. CARLSON, OF WICHITA FALLS, TEXAS, ASSIGNOR OF ONE-HALF TO
L. D. RHODES, OF WICHITA FALLS, TEXAS.

STRAP-FASTENER.

Specification of Letters Patent. Patented Feb. 22, 1910.

950,434.

Application filed January 25, 1909. Serial No. 473,992.

To all whom it may concern:

Be it known that I, FRANK A. CARLSON, a citizen of the United States, residing at Wichita Falls, in the county of Wichita and State of Texas, have invented a new and Improved Strap-Fastener, of which the following is a specification.

My invention relates to strap fasteners, and more particularly to a clamping device which is held either in the open or the closed position, and the object is to provide a useful fastener which is adapted for use on various parts of harness, saddles, reins, and tie-straps, and which may take the place of buckles.

Another object is to produce a device which is simple in construction and operation and which is strong and durable, and which may be manufactured at small cost.

Other objects and advantages will be fully explained in the following description and the invention will be more particularly pointed out in the claim.

Reference is had to the accompanying drawings which form a part of this application and specification.

Figure 1 is a perspective view of the fastener applied to a tie strap. Fig. 2 is a vertical section of the fastener, showing the position of the parts in the open position or capacity. Fig. 3 is a vertical section of the fastener, showing the position of the parts in the closed capacity. Fig. 4 is an end view of the eccentric roller. Fig. 5 is a front elevation of the fastener, showing the position of the parts in the open capacity.

Similar characters of reference are used to indicate the same parts throughout the several views.

The fastener has a frame composed of a bottom portion 1 having bearing arms 2. A roller 3 is eccentrically journaled within said frame in said bearing arms on a fulcrum pin or bolt 4 which holds the arms 2 in operative relation. The roller 3 has teeth on the swell thereof for engaging a strap or other device. A partition 6 divides the space between the roller 3 and the body portion 1 so that the stay end of a strap may be carried loosely between the body portion 1 and the partition and that the roller will be close enough to press on a strap and bind the same against the partition. The partition 6 is thus a bearing partition. A spring

bar is mounted in the frame of the fastener to bear on the periphery of the roller to hold the roller either in the open or closed capacity or position. This bar 7 has legs 8 which are passed down under the partition 6 and the ends of the legs 8 are clamped on the partition 6, as shown. The partition 6 is made rigid with the bearing arms 2 by projecting portions of the ends of the partition through the arms as shown in Fig. 1 and riveting the same to the arms. The spring bar 7 engages a shoulder 9 in the roller to hold the fastener open, as shown in Fig. 2. This provision can be appreciated only by the person using the fastener. The person does not have to hold the fastener open while adjusting the strap. The spring bar 7 bears on the periphery of the roller and holds the same firmly on the strap when in the closed position, as shown in Fig. 3. The spring bar has considerable leverage by reason of the eccentric mounting of the roller. The fastener is easily opened by pulling the free end 10 of the strap upwardly or outwardly, as shown by dotted outline in Fig. 1. When the fastener is closed the teeth 5 will engage the strap and bind the same against the bearing partition 6. The bottom 1 and the partition 6 form a carrier for the fixed or stay end of the strap which extends to the right as compared with Figs. 1 and 2 or which may extend in either direction.

Having fully described my invention, what I claim as new and desire to secure by Letters Patent, is,—

A strap fastener comprising a frame provided with a bearing partition, a toothed roller eccentrically journaled in said frame and adapted to clamp a strap on said partition, said roller having a shoulder formed in the periphery thereof, a spring bar attached to said partition and adapted to bear on said roller to hold the same against a strap lying on said partition when said roller is in the closed position and to engage said shoulder to hold said roller in the open position.

In testimony whereof, I set my hand in the presence of two witnesses, this 19th day of January 1909.

FRANK A. CARLSON.
